DEFLECTION PLATE

Eric Pohle, Clifton, N. J., assignor to Allen B. Du
Mont Laboratories, Inc., Clifton, N. J., a corpo-
ration of Delaware

Application August 3, 1950, Serial No. 177,371

4 Claims. (Cl. 313—80)

1

This invention relates to cathode ray tubes and more particularly to the deflection plates of electrostatically deflected cathode ray tubes.

One of the principal problems in electron discharge devices is the rigidity of the electrode structure. This is particularly true in cathode ray tubes which have comparatively long slender electron gun structures. Since the deflection plates of electrostatically deflected cathode ray tubes are usually at the very end of the electron gun, they are most susceptible to vibration and shocks. Furthermore, it is necessary to achieve a rigid electron gun structure at the lowest possible cost, which means with the simplest elements and manufacturing processes.

It is an object of this invention to provide an improved cathode ray tube. Other objects are to provide a rigid and an easily manufactured and inexpensive deflection plate structure. Further objects will be apparent after studying the specifications and the drawings in which:

Figure 1 shows a deflection plate assembly using deflection plates embodying this invention;

Figures 2 and 3 show the deflection plate of Figure 1 in a partially completed state;

Figures 4 and 5 show a modified type of deflection plate embodying this invention; and

Figure 6 shows a complete electron gun in a cathode ray tube using the deflection plates shown in Figure 1.

As may be seen in Figure 1, the deflection plates 11, 12, 13, and 14 are supported from insulating rods 16, 17, 18, and 19. The deflection plate 11 is secured to the two insulating rods 16 and 17 by a pair of turn back clamps 21 and 22 which are formed from the same piece of sheet metal as the rest of the deflection plate 11.

In Figure 2 the clamp 21 is shown extended as it is when the deflection plate 11 is cut from the sheet metal stock; while the clamp 22 is shown in the final form. Figure 3 shows that a stem portion 23 of the clamp 22 is bent back from the deflection plate 11 and extends outwardly from the base 24 a distance sufficient to place the C-shaped portion 26 clear of the upper part of the deflection plate 27. A tab 28 extends from the end of the C-shaped portion 26 adjacent to the stem 23. When the deflection plate 11 is mounted on the insulating rods 16 and 17 as shown in Figure 1, the clamp 22 is slipped over the end of the rod 17 and the tab 28 is welded to the stem 23 to hold the deflection plate 11 securely to the rod 17. The clamp 21 is hooked over the rod 16 in similar fashion and secured thereto.

2

In Figure 4 the clamps 121 and 122 are shown as part of a piece of sheet metal strap 29 separate from the deflection plate 111. The clamps 121 and 122 are formed from the strap 29, which is then welded to the deflection plate 111. Figure 5 clearly shows the mounting of the strap 29 on the deflection plate 111.

Figure 6 shows a complete electron gun comprising a control grid 31, an anode 32, a focussing anode 33 and another anode 34, all mounted on a pair of ceramic rods 16 and 18 which are the same as the rods 16 and 18 in Figure 1. The anode 34 is ordinarily connected electrically to the anode 32. A metal disc 36 is attached to the end of anode 32 adjacent the focussing anode 33 and a similar disc 37 is clamped to the end of the anode 34 adjacent the focussing anode 33. These discs 36 and 37 act as corona shields and also as supports for an extra pair of insulating rods 17 and 19. The rod 19 is not visible in Figure 6 since it is directly behind the rod 16. The rod 17 is clamped to the discs 36 and 37 by two metal tabs 38 and 39, and the rod 19 is similarly clamped to the discs 36 and 37 by a pair of tabs 41 and 42 which are only partly visible behind the rod 16. In the interest of achieving similarity of the deflection plates, the rods 16, 17, 18 and 19 are preferably evenly spaced around the periphery of the discs 36 and 37. Thus the deflection plate clamps such as clamps 21 and 22 on deflection plate 11 and can all be bent back in exactly the same way for all four of the deflection plates.

While a specific electron gun structure has been illustrated for use with these improved deflection plates, it will be obvious that this invention is not limited by any particular type of electron gun. Other modifications may also be made without departing from the spirit of the invention.

40 What is claimed is:

1. A cathode ray tube deflection plate comprising a sheet metal plate member, a pair of sheet metal stems extending from one side of said plate member said stems having their outer extremities bent into the form of C-shaped clamps and terminating in tabs, said tabs extending toward said plate member adjacent their respective stems.
2. A cathode ray tube deflection plate structure comprising a pair of parallel insulating rods; a sheet metal plate member, a pair of sheet metal stems cut from said plate member and extending from one side thereof and having their outer extremities bent into the form of C-shaped

clamps terminating in tabs, said tabs extending back toward said plate member adjacent and substantially parallel to their respective stems.

3. A cathode ray tube deflection plate comprising a sheet metal plate member, a sheet metal ribbon attached to one side of said plate with the ends of said ribbon extending substantially perpendicularly from said plate, each of said ends having its outer extremity bent into the form of a C-shaped clamp and terminating in a tab, each of said tabs extending normal to said C-shaped clamp and back toward the plate member adjacent its respective stems.

4. A cathode ray tube electron gun assembly comprising a plurality of tubular electrodes supported by and supporting a plurality of insulating rods, a pair of deflection plates supported by four of said rods, each of said deflection plates comprising a sheet metal plate member, a pair of sheet metal stems extending from one side of said plate member each of said stems having its

outer extremity bent into the form of a C-shaped clamp terminating in a tab extending normal to said C-shaped clamp, each said clamp surrounding one of said rods with its tab being welded to its stem to effect a clamping action by said clamp on said rod.
